UNITED STATES PATENT OFFICE.

CHARLES AUGUSTUS BUTLER, OF BARTLESVILLE, OKLAHOMA.

EXPANSION-BIT.

No. 890,493.

Specification of Letters Patent.

Patented June 9, 1908.

Application filed September 4, 1907. Serial No. 391,334.

To all whom it may concern:

Be it known that I, CHARLES A. BUTLER, a citizen of the United States, and a resident of Bartlesville, District 27, Oklahoma, have 5 invented new and useful Improvements in Expansion-Bits, of which the following is a full, clear, and exact description.

This invention has reference to improvements in expansion bits more especially designed for the drilling of oil and Artesian wells, and has for its object primarily to provide a bit which is adapted to drill a hole of sufficient diameter at a single operation for receiving the well casing, and permit of the 15 said casing being inserted in the hole as the drilling operation proceeds.

It is necessary in drilling wells through loose formations to sink the casing at the time of drilling in order to support the walls 20 of the hole and prevent the earth from caving in. This has heretofore been done by first drilling a hole of substantially the internal diameter of the casing and thereafter enlarging the hole as the casing is sunk, with a tool 25 known as an "under reamer". With my invention the drilling is accomplished with less labor, and the time required for the work is correspondingly diminished.

Reference is to be had to the accompanying 30 drawings forming a part of this specification, in which similar characters of reference indicate corresponding parts in all the views.

Figure 1 is a side elevation of one embodiment of my improved bit, showing it in position 35 for drilling a hole for receiving the well casing; Fig. 2 is a view similar to Fig. 1, with the bit contracted as when it is withdrawn from and inserted into the well casing, and Fig. 3 is a cross-section of the tool on the 40 line 3—3 of Fig. 1, looking in the direction of the arrows.

The tool is preferably entirely constructed of steel and is composed of a body having a longitudinal central wedge-shaped slot extending 45 a considerable portion of its length and dividing it into side members 5, each of which is provided at its lower extremity with a double cutting edge 6. Received between the members 5 within the slot of the body of 50 the bit is a wedge-shaped member 7 having a corresponding cutting edge 6^a, and adapted to expand the side members 5 and bring the cutting edge 6^a into substantial register with the cutting edges 6 when the wedge is forced 55 to the top of the slot, as shown in Fig. 1.

As best shown in Fig. 3, the body of the

tool is of rounding form with flattened sides, each side being provided at one edge with a rib 8 which is arranged diagonally opposite the rib of the opposite side. The side members 5 of the body are also connected together at both sides near their cutting edges by overlapping projections or plates 9, one of which is transversely slotted and the other carrying an engaging pin 11 which acts as a 60 stop to prevent the further separation of the members 5 when the wedge 7 is forced to the top of the slot between them. These plates or projections 9 are made as an integral part with their respective members 5, as are also 65 plates or projections 12 provided on the opposite sides of the wedge member 7 near its smaller end. These last-named plates or projections, in connection with the plates 9, not only serve to guide the wedge and prevent 70 any lateral displacement thereof, but also operate as a stop, as shown in Fig. 2, to prevent the complete separation of the wedge from the body of the bit when the latter is contracted. The wedge member 7 75 is constructed with grooves 13 at opposite sides for the discharge of the cuttings, and are provided above the projections 12 with pivotally suspended dogs 14, the said dogs being substantially L-shaped arranged at 80 opposite sides of the tool and serve to engage with the bottom edge of the well casing when withdrawing the bit therefrom. This engagement of the dogs with the casing, as the bit is withdrawn from the well, forces the 85 wedge member downwardly with respect to the side members until the projections 12 encounter the projections or plates 9, at which time the dogs swing out of the path of the casing and permit of the casing passing 90 thereover. This is made possible by providing the inner edges of the ribs 8, against which the back of the dogs bear, with rabbeted portions 15 which are of sufficient extent to permit of the dogs moving within 95 the outline of the tool, whereby they may readily pass through the casing. The shank of the tool is preferably constructed with a threaded neck 16, as shown in dotted outline in Fig. 1, for attaching it to the drill rod, and 100 is further provided with an angular portion 17 for removing and applying the bit to the drill rod with a wrench.

The construction of the bit as above outlined and shown in the accompanying drawings while being the preferred form of my invention, may obviously be modified in 110

numerous minor particulars within the scope of the annexed claims.

Having thus described my invention, I claim as new and desire to secure by Letters 5 Patent:

1. An expansion bit comprising a body having a tapering opening substantially longitudinally arranged and dividing the body into two side members which are provided with cutting edges, and a tapering central member fitting within said opening and having a cutting edge adapted to register with the cutting edges of said side members. 10
2. An expansion bit comprising a body having a longitudinal slot dividing it into two side members which are provided with cutting edges, and a wedge member fitting into said slot and provided with a cutting edge. 15
3. An expansion bit comprising a body having a longitudinal slot dividing it into two side members provided with cutting edges, a wedge member arranged within said slot adapted to expand the side members and provided with a cutting edge, and dogs pivotally suspended from the wedge member for withdrawing it from the side members. 20
4. An expansion bit comprising a body having a longitudinal wedge-shaped slot dividing it into two side members and provided with cutting edges, a wedge member within said slot adapted to expand the side members and having a cutting edge, and means for positively preventing the further separation of said side members when fully expanded by the said wedge member. 25
5. An expansion bit comprising a body having a longitudinal wedge-shaped slot dividing it into two side members, a wedge member fitting within said slot adapted to expand the side members, means for positively preventing the further separation of the side members when fully expanded by the wedge member, and means coacting with the last-named means for preventing the complete removal of the wedge member from between the side members. 30

6. An expansion bit comprising a body having ribs arranged longitudinally at diagonally opposite edges and provided with a wedge-shaped slot dividing it into two side members, a wedge member fitting within said slot adapted to expand the side members, and dogs pivotally suspended on the wedge member and adapted to bear against said ribs for the purpose described. 55

7. An expansion bit comprising a body having a longitudinal wedge-shaped slot dividing it into two side members provided with cutting edges, a wedge member fitting into said slot adapted to expand the side members and provided with a cutting edge, ribs formed on the side members having rabbeted portions, and dogs pivotally suspended on the wedge member adapted to bear against said ribs and pass into the rabbeted portions thereof when the wedge member is withdrawn. 60

8. An expansion bit comprising a body having a longitudinal wedge-shaped slot dividing it into two side members, a wedge member within the slot adapted to expand the side members, means connecting the side members together operating to positively prevent the further separation thereof when the side members are fully expanded by the wedge member, means carried by the wedge member coacting with said last-named means to provide a stop for preventing the complete withdrawal of the wedge member from the side members, a rib longitudinally formed on one of the side members having a rabbeted portion, a dog pivotally suspended on the wedge member adapted to bear against said rib and pass into the rabbeted portion thereof when the first and last-named means contact. 70

In testimony whereof I have signed my name to this specification in the presence of two subscribing witnesses.

CHARLES AUGUSTUS BUTLER.
